TUNING RANGE ADJUSTMENT DEVICE

Walter van B. Roberts, Princeton, N. J., assignor
to Radio Corporation of America, a corpora-
tion of Delaware

Original application March 9, 1933, Serial No.
660,124. Divided and this application Febru-
ary 14, 1936, Serial No. 63,825

2 Claims. (Cl. 250—40)

My present invention relates to tunable radio frequency circuits, and more particularly to tunable circuits including fixed tuning adjustment reactance elements, and is a division of my application serial No. 660,124, filed March 9, 1933 patented March 24, 1936 as U. S. P. 2,034,773.

The object of the present invention is to provide a tuning means for a resonant radio frequency circuit which can readily be changed from a condition which covers a wide range of frequencies to a condition which covers only a narrow band of frequencies with the same range of adjustment of the tuning mechanism.

The novel features which I believe to be characteristic of my invention are set forth in particularity in the appended claims, the invention itself, however, as to both its organization and method of operation will best be understood by reference to the following description taken in connection with the drawing in which I have indicated diagrammatically several circuit organizations whereby my invention may be carried into effect.

In the drawing:

Figs. 1 and 2 show alternative embodiments of the basic principle of the present invention applied to a band spreader device for tunable radio frequency circuits and,

Fig. 3 graphically illustrates the operation of the arrangement of Figs. 1 and 2.

The basic principle of the present invention is utilized to provide a tuning means which can readily be changed from a condition which covers a wide range of frequencies to a condition which covers only a narrow band of frequencies with the same range of adjustment of the tuning mechanism.

In both Figs. 1 and 2, the grounded antenna circuit A_2 is coupled to the input electrodes of an amplifier tube 20 by means of a radio frequency transformer M , the secondary coil L_8 of which is connected between the grid and cathode of the amplifier tube. The anode and cathode of the amplifier tube may be coupled to a succeeding amplifier stage of any well known type of receiver. Such a receiver may be of the tuned radio frequency amplifier type, a superheterodyne receiver, or even a super-regenerative receiver. The variable tuning condenser C_6 is connected across the fixed inductance coil L_6 . However, a large fixed condenser K_1 is connected substantially in series with the variable condenser C_6 , while a small fixed condenser K_2 is arranged for connection substantially in shunt with the variable tuning condenser C_6 .

A switch device is employed for selectively connecting and disconnecting the fixed condensers K_1 and K_2 . This switching device in Fig. 1 comprises a terminal a connected to one side of the tuning condenser C_6 and a second terminal b connected to one side of the fixed condenser K_2 , and a movable switch arm 21 connected to the grid of tube 20 . In Fig. 2, the switch arm 21 is connected to one side of the tuning condenser C_6 , the terminal a is connected to the grid of tube 20 , and the terminal b is connected to one side of the fixed condenser K_2 .

In both Figs. 1 and 2, when the switch arm 21 is connected to terminal a the tuning condenser is directly connected across the inductance coil L_6 and the shunt condenser K_2 is disconnected. Therefore, the range of tuning will be as great as the ratio of the square root of the maximum and minimum capacities of the variable condenser together with tube and coil capacities. With the usual type of variable condenser this range of frequencies would be about 3:1.

With the switch arm 21 on terminal b the maximum capacity across the inductance coil L_6 is reduced by series condenser K_1 , while the minimum capacity is increased by the condenser K_2 . By properly choosing the values of K_1 and K_2 the range of variation of circuit capacity may be made as small as desired.

Fig. 3 graphically shows how the frequency of the resonant circuits of Figs. 1 and 2 vary with tuning condenser adjustment according as the switch arm 21 is in position a or position b . With the capacities K_1 and K_2 so chosen as to make the minimum capacity across coil L_6 greater in switch position b than in a , and the maximum capacity across coil L_6 less in b than a , it is obvious that the curves of Fig. 3 must cross each other, and this position of the crossing may be chosen at will by properly choosing the relative values of K_1 and K_2 . For example, if it is desired in the case of Fig. 1 to have the crossing point occur when the variable capacity has a value C_m , all that is necessary is to make

$$K_2 = \frac{C_m^2}{K_1 + C_m}$$

The arrangements shown in Figs. 1 and 2 are particularly adapted to amateur reception. The amateur frequency bands are located in harmonic relation with each other. That is to say, each band is at approximately twice the frequency of the preceding one. If now a separate coil is provided for each band, the range of tuning available with an ordinary condenser is

at least 2:1 and, hence, is such as to make possible reception of all frequencies between the amateur bands, when desired, by setting the switch arm 21 on position *a*.

5 However, when receiving messages lying within the amateur bands, the switch is used on position *b*, the condensers K_1 and K_2 being chosen to have such values as will cause the frequencies in the amateur band to be spread out over a 10 considerable portion of the dial adjustment and thus greatly facilitate tuning. When plug-in coils are used for the various bands, it is well to choose the inductances so that for each coil the center of the desired band occurs at $C=C_m$ =the 15 same for each coil. This avoids the necessity to readjust K_1 or K_2 to center the band on the setting C_m .

While I have indicated and described several 20 systems for carrying my invention into effect, it will be apparent to one skilled in the art that my invention is by no means limited to the particular organizations shown and described, but that many modifications may be made without 25 departing from the scope of my invention as set forth in the appended claims.

What I claim is:

1. A resonant network comprising a variable 30 condenser and coil that tune over a wide frequency range, which wide range includes a narrow frequency range, the mid-frequency of said narrow range being secured by adjustment of the variable condenser to a capacity C_m , a fixed condenser K_1 in series with said first condenser, and a fixed condenser K_2 in shunt with said first condenser, means for selectively disconnecting the condenser K_2 from across the first condenser and shorting condenser K_1 , the capacity of condenser 35

K_1 being chosen smaller than capacity C_m , and there existing the following relation

$$K_2 = \frac{C_m^2}{K_1 + C_m}$$

whereby the resonant frequency is the same for both switch positions, but the range of tuning is very much less with the condensers K_1 and K_2 in circuit.

2. In combination, an inductance element, a 10 variable condenser having a sufficiently large ratio of maximum capacity to minimum capacity to resonate said inductance over a relatively large frequency range when operatively associated therewith, a fixed condenser of capacity K_1 which is smaller than a value C_m , switching means for connecting said fixed condenser in series relation with said variable condenser, a second fixed condenser of capacity K_2 , said switching means being adapted to connect the second fixed condenser 15 in shunt relation to the said variable condenser, the capacity of said second fixed condenser being 20

$$\frac{C_m^2}{K_1 + C_m},$$

25 the capacity C_m being the capacity of the variable condenser when adjusted to resonate the said inductance to the mid-frequency of its range of adjustment, whereby the said inductance is resonated to the same mid-frequency when the said variable condenser is adjusted to the value C_m regardless whether the aforesaid switching means 30 is set to connect said fixed condensers effectively with said variable condenser or not, but whereby the range of tuning is reduced by switching said fixed condensers into connection with said variable condenser.
